AUTOMOBILE SIGNAL LAMP

Filed Aug. 6, 1927.

INVENTOR
George P. Ohlgart
By Charles B. Mann, Jr.

ATTORNEY

UNITED STATES PATENT OFFICE.

GEORGE P. OHLGART, OF BALTIMORE, MARYLAND.

AUTOMOBILE SIGNAL LAMP.

Application filed August 6, 1927. Serial No. 211,066.

This invention relates to improvements in lamps for automobiles and has for its object to provide an improved arrangement of lamps and supporting means together with a novel form of circuits for the same.

The structure embodying the invention as illustrated in the drawing is especially shown as a parking lamp although the same may readily be utilized in a tail-lamp.

10 The object of the invention is to provide a novel arrangement of lamps and circuits for parking or tail lights on automobiles whereby the burning out of one lamp will automatically form a circuit through a second lamp in the same lamp housing so that light will be supplied by said second lamp when the other lamp breaks or burns out.

The invention is illustrated in the accompanying drawing, wherein,—

20 Fig. 1 shows a portion of an automobile including part of a rear wheel and mud-guard with the lamp in place thereon.

Fig. 2 illustrates the lamp in sectional elevation.

25 Fig. 3 shows the bottom of the lamp structure with the circuit connection thereto, and

Fig. 4 illustrates the lamps, the electro-magnetic switch elements and the circuits 30 in a purely diagrammatic manner.

Referring to the drawing, the numeral 5 designates the housing of the lamp which, in this instance, has a substantially rectangular base 6 entirely open at the bottom and having a hollow barrel or head 7 extending horizontally across the rectangular base but with the space within the head and base in communication.

Each end of the hollow barrel-head is provided with a lens,—that one which is designated 8 in the drawing being at the front end while that which is designated 9 being at the rear.

In practice, it is customary to provide a 45 white front lens 8 while the rear lens 9

is usually of red glass so that a white light will be displayed forward while a red light will be shown at the rear.

In the base of the housing 6 I provide a case 10, having a lining of fiber or insulating material 11 and this lining has a central opening or chamber 12 in which there are two small electro-magnets 13 and 14 respectively. These electro-magnets have, in this instance, a position in the case so that their 50 cores 15 and 16 extend horizontally.

In the case I mount a spring armature-plate 17, which latter extends in a direction so as to cross the ends of the two cores 15 and 16 of the magnets and in such proximity thereto as to be attracted by the magnets when the latter are energized, but to spring away from the said cores when the magnets are deenergized.

A contact 18 is also provided in the case 65 so that when said armature-plate 17 is released by the electro-magnets and springs away therefrom said plate will engage said contact 18. On top of the case 10 I mount two lamp sockets 19 and 20 and in the socket 70 19, I provide a lamp 21, while in the socket 20 there is a lamp 22. These two lamps are of unequal voltage in that the lamp 21 is of a 3-4 voltage while the lamp 22 is of a 6-8 voltage.

75 The circuit involved is a single wire circuit with a return through ground and by reference to Fig. 3, the circuit connections will be explained.

The battery is designated 23 while the 80 switch is shown at 24.

From the battery, there is a wire 25 leading to the switch 24 and from the switch there are wires 26 and 29 which lead to the electro-magnet 14.

85 Another wire 28 connects the electro-magnets 14 and 13 and a wire 27 extends from electro-magnet 13 to the center contact of the lamp-socket 19.

A wire 31 connects the two lamp-sockets 90

19 and 20 and a wire 30 forms a ground connection from the lamp-socket 20 back to the battery.

A branch wire 33 leads from wire 29 and 5 connects with one end of the armature-plate 17, while a wire 32, connects the stationary contact 18 with the center contact of lamp-socket 20.

From the base of the case 10, there is a 10 post 34 which serves as a binding post and also as a means for securing the structure to a mud guard or other part of an automobile.

When the switch 24 is closed, a circuit 15 will be established from the battery 23 through wire 25 to and through the switch 24; then by wires 26 and 29 to and through the electro-magnets 14—13 thus energizing the latter and holding the armature-plate 17 20 against the cores 16—15 of the magnets, then the circuit is continued by wire 27 to the center contact of lamp-socket 19 and through low voltage lamp 21; then from lamp-socket 19 to lamp-socket 20, and re- 25 turn by ground or wire 30 to the battery.

It will thus be seen that this normal circuit includes the low voltage lamp 21 and both electro-magnets and that as those magnets are energized, the armature-plate 17 will 30 be held back away from contact 18 and prevent the closing of a circuit through the other lamp 22.

As both lamps 21 and 22 are located in the barrel or head 7 between the front and rear 35 lenses 8 and 9 and both of those lamps are of clear glass, the illumination of either of them will project light beams both ahead and to the rear and the presence of one lamp, which is not illuminated but is of clear 40 glass, between the illuminated lamp and one of the lenses will not blanket or cast a shadow on that lens.

In case the lamp 21 should burn out or 45 become broken, the normal circuit, just described, will be interrupted whereupon the electro-magnets will become deenergized and the armature-plate 17 will then spring away from the cores 15—16 of the magnets and will engage the contact 18.

Immediately upon engagement of armature-plate 17 with the contact 18, a substitute circuit will be formed through the higher voltage lamp 22,—the circuit then being as follows:

From battery 23, wire 25, switch 24 and 55 wires 26 and 33 to the fixed end of the armature-plate 17; then through said plate, (which at this time will engage the contact 18) to the said contact 18; then by wire 32 60 to the center lamp-contact of lamp-socket 20 and through the lamp 22; then return from lamp-socket 20 by ground or wire 30 to battery.

This substitute circuit does not include the 65 electro-magnets and consequently a lamp

of higher voltage is utilized in this circuit.

It will thus be seen that I arrange the two lamps in the case or barrel between two lenses,—one of the lamps being of a lesser voltage than the other and the circuit 70 through the lamp of lesser voltage including electro-magnets which cut off the current to the lamp of the higher voltage.

In this manner, I provide two lamps in the one barrel, and the burning out or breaking 75 of one of those lamps will automatically close a circuit through the other lamp and illuminate the latter so that the signal will be maintained even though the normal circuit 80 through the one lamp becomes interrupted.

Having described my invention, I claim—

1. In an automobile signal lamp the combination with a lamp-housing having two spaced lens-openings and a hollow base below said two lens-openings, of a detachable case in the housing-base said case carrying two lamp-sockets on the upper side thereof which sockets are electrically connected, an electro-magnet means enclosed in said detachable case, an armature also in said detachable case which is held in one position by said electro-magnet means when the latter is energized, a stationary contact also in the case which contact is to be engaged by 90 the armature only when the electro-magnet means is deenergized, a separate lamp in each of said two lamp-sockets said two lamps being positioned in the lamp-housing between the two lamp-openings and one of 100 said lamps having a center contact in constant connection with the said stationary contact, electric circuit connections including one of said lamps, the electro-magnet means both lamp sockets and a ground, and 105 another set of electric circuit connections formed when the electro-magnet means is deenergized, including the armature, the stationary contact, the center contact of the other lamp and its socket and a connection 110 to the ground the said case and the electrical elements therein being removable as a unit from the base of the lamp-housing.

2. In an automobile signal lamp the combination with a lamp-housing having two 115 spaced lens-openings and a hollow base below said two openings, of a detachable case in said housing-base said case carrying two lamp sockets on the upper side thereof which sockets are electrically connected, an 120 electro-magnet means enclosed in said detachable case, a stationary contact in said detachable case, an armature also in said case which armature, when the electro-magnet means is energized, is held out of engagement with said contact, a lamp of one voltage in one of said two lamp-sockets, another lamp of a lower voltage in the other of said lamp-sockets, normal circuit 125 connections from a single current-supply in- 130

cluding the lamp of lesser voltage, the electro-magnet means both lamp sockets and a ground, and another set of electric circuit connections from the same current supply 5 and formed when the electro-magnet means is deenergized including the said armature, the stationary contact, the center contact of the lamp of greater voltage and its socket and the ground.

10 In testimony whereof I affix my signature.

GEORGE P. OHLGART.
